UNITED STATES PATENT OFFICE

RALPH C. SIMMONS, OF SPOKANE, WASHINGTON

POWER MACHINE

Application filed December 14, 1929. Serial No. 414,203.

My invention relates to power machines and certain objects of the invention are to provide a turbine driven machine having a system of gears so arranged that a gain in power is accomplished by the driven elements over the driving elements. Further objects of the invention are to provide a power machine comprising novel details of construction and arrangement as hereinafter set forth.

With the above and other objects in view which will appear as the description proceeds, the invention consists of the novel construction, adaptation, combination and arrangement of parts hereinafter described and claimed. These objects are accomplished by devices illustrated in the accompanying drawings; wherein:—

Figure 1 is a top plan view of the machine with a portion of the housing broken away;

Fig. 2 is a view in central vertical section taken substantially on a broken line 2, 2 of Fig. 1;

Fig. 3 is a view in end elevation;

Fig. 4 is a view in side elevation;

Fig. 5 is a detail view partly in vertical section and partly in elevation and showing one of the nozzles in its relation with one of the turbine wheels;

Fig. 6 is a view in central vertical section of the rotary coupling taken on a broken line 6, 6 of Fig. 4; and

Fig. 7 is a view in perspective of a lubricator splash paddle.

Referring to the drawings throughout which like reference numerals designate like parts, the numeral 5 indicates a power storage tank which may contain compressed air, steam or water. This power medium passes from the storage tank through a pipe 6 and may be controlled by a valve 7. Said pipe is provided at its lower end with a T-joint 8 having pipes 9 extending in opposite directions from either end thereof.

Referring to Figs. 4 and 6 of the drawings, the T-joint 8 is connected to the pipe 6 by means of a rotary coupling comprising a female member 10 threaded onto the lower end of said pipe and a male bushing member 11 threaded into the lower end of said female

member with the upper flange end 12 of said T-joint interposed between said bushing and female member whereby the T-joint may revolve freely as will be understood.

The outer ends of the pipes 9 are threadedly connected to elbows 13 each of which is threadedly provided with a discharge nozzle 14. The outlet for each nozzle is directed against the teeth 15 of turbine wheels 16. Said turbines are preferably made of three-ply metal discs riveted together with said teeth formed on the middle disc as most clearly shown in Figs. 1 and 2 of the drawings.

The turbine wheels 16 are each keyed to the ends of a shaft 17 and a gear 18 is keyed to an end portion of said shaft. Said gear is arranged to travel around on an annular toothed track or rack 19 that is fixedly mounted on the upper periphery of an inverted stationary hollow outer cone shaped support 20. The truncated vertex end of said support is secured at 21 to a hollow base cone member 22 whose bottom is secured to a bed plate 23. The vertex end portion 24 of said base cone member projects into the inverted outer cone support for reasons presently set forth.

An inner cone member 25 is adapted to revolve on the vertex end portion of the cone member 22 with ball bearings 26 interposed therebetween. The shaft 17 is supported by said inner cone member in bearings 27 and an upper housing 28 is carried by said member to which it is connected by means of brackets 29. Side brackets 30 and a central bracket 31 extend upwardly from said housing in support of the pipes 9. A dish shaped bracket 32 resting on the inner bearings 27 serves to support the central portion of the upper housing.

It will now be apparent that the outer cone member or support 20 together with its toothed track 19 and the base cone member 22 are the only stationary parts of the machine. All of the other members taken collectively revolve in a horizontal direction around a vertical axis with the ball bearings 26 serving as a lower support and the rotary pipe coupling serving as an upper support. At the same time the turbine wheels 16, shaft 17 and gear 18 rotate in a vertical direction.

A flange member 33 that may be integral or fixed to the periphery of the outer cone support 20 and enveloping the lower peripheral edge portion of the housing 28 serves as a closure between said cone and housing as will be understood.

A bevel gear 34 keyed to the central portion of the horizontal shaft 17 meshes with a corresponding gear 35 that is fixed to the upper end of a vertical shaft 36. Said vertical shaft has its upper bearing 37 in the vertex portion of the cone member 22 and its lower bearing 38 in the base portion of said cone member. An adjusting nut 39 provides means whereby said vertical shaft may be adjusted.

The vertical shaft 36 is provided at its lower end portion with a bevel gear 40 that meshes with a similar gear 41 mounted on the inner end of a shaft 42 which is journaled in bearings 43 and 44 forming an integral part of the cone member 22. A pulley 45 is keyed to said shaft from which the power of the machine is taken as will be understood. A number of splash paddles 46, as shown in detail in Fig. 7, are secured to the lower end portion of the inner cone member 25 and travel therewith whereby the oil housed within the bottom of the outer stationary cone support 20 is thrown upwardly to lubricate the bearing parts of the machine.

In an explanation of the operation and advantages of the machine it must first be understood that all of the gears 18, 34, 35, 40 and 41 are of the same circumference and have the same number of teeth. When the power medium strikes the turbine wheels 16, the shaft 17 is rotated thus causing the gear 18, which is keyed thereto, to travel around the toothed track 19 carrying all of the members therewith except the stationary members as hereinbefore set forth.

The circumference of the track 19 is six times the circumference of the gear 18 and has six times as many teeth. Therefore in one revolution around said track said gear will make six revolutions and, of course, the shaft 17 and gear 34 will also make six revolutions in a vertical plane. But, at the same time, the gear 34 has made an extra revolution in its horizontal movement. This horizontal revolution of the gear 34 is equally effective as its six vertical revolutions in rotating the gear 35 with which it is in mesh.

Thus, in every single revolution around the track 19, the gear 34 will cause the gear 35 to gain one revolution, or in other words the gear 35 will make seven revolutions to every six revolutions of the gear 34 and so will the pulley 45 whose movement is directly connected therewith. It will now be apparent that a gain in speed and power of the driven elements over the driving elements is accomplished.

Having thus described my invention, it be-

ing understood that minor changes may be resorted to in its construction without departing from its scope and spirit, what I claim and desire to secure by Letters Patent of the United States is:—

1. A power machine comprising a turbine driven shaft arranged to rotate on its axis, an annular toothed track, a gear fixed to an end portion of the shaft and in mesh with said toothed track whereby said shaft is bodily rotated, a bevel gear fixed to the central portion of the shaft, another bevel gear in mesh with said bevel gear whereby the axial and bodily rotation of the shaft will cause an extra revolution of the last named bevel gear for each bodily revolution of the shaft.

2. A power machine comprising a turbine driven shaft arranged for axial rotation, a gear fixed to an end portion of the shaft, an annular toothed track, outer conical supporting means for the track, said gear in mesh with the track whereby the shaft is bodily rotated, an inner conical support for the shaft revolvably mounted on the outer conical support, a bevel gear fixed to the central portion of the shaft, said gear in mesh with another bevel gear whereby the axial and bodily rotation of the shaft will cause an extra revolution of the last named bevel gear for each bodily revolution of the shaft, and a train of shafts and gears for the last named bevel gear for delivery of the power from the machine.

In testimony whereof I affix my signature.

RALPH C. SIMMONS.
